UNITED STATES PATENT OFFICE.

DAVID W. BRUNTON, OF DENVER, COLORADO.

MINE-TIMBER.

SPECIFICATION forming part of Letters Patent No. 759,418, dated May 10, 1904.

Application filed February 4, 1904. Serial No. 191,975. (No model.)

To all whom it may concern:

Be it known that I, DAVID W. BRUNTON, a subject of the King of Great Britain, (but having declared my intention of becoming a citizen of the United States,) residing at Denver, in the county of Denver and State of Colorado, have invented a certain new and useful Improvement in Mine-Timbers, of which the following is a full, clear, and exact description.

10 In the use of round mine-timbers formed with a beveled joint it often happens that blasts are fired close to the timbers after the timbers have been placed in position, but before they are securely wedged against the 15 walls and roof of the mine-openings, and as a result the force of the explosion often drives the timbers out of position by causing them to slide along the beveled sides of the joint.

20 One object of the present invention is to obviate the dislocation of the joint in round mine-timbers having beveled ends and to resist shock from any position and maintain the joint in position when the explosion occurs.

25 The invention consists in a post, cap, and girth, each having a rectangular or square tenon centrally arranged and with adjacent rearwardly-beveled edges, so that while these 30 rectangular tenons are matched and adapted to prevent the longitudinal dislocation of the joint the beveled edges serve to utilize the full circumference of the mine-timbers, with all the incidental advantages set forth in my 35 Patent No. 692,111, dated January 28, 1902.

40 In the accompanying drawings, illustrating the invention, in the several figures of which like parts are similarly designated, Figure 1 is a side elevation and end development of the post. Fig. 2 is a side elevation and end development of the cap. Fig. 3 is a side elevation and end development of the girth. Fig. 4 is a perspective view of these three timbers about to be assembled in a joint. Fig. 5 is a 45 perspective view of the three timbers assem-

bled in a joint and ready to receive any additional timbers.

a is the post of round timber having the rectangular end tenons *b* and the four slanting or beveled edges *c* adjacent thereto.

50 *d* is the cap having the end tenons *e*, which rise from subtenons *f*, which in turn rise from flat bases *g* at the ends of the timber, the said tenons *f* having two parallel walls flush with the walls of the tenon. The bevels *h* diverge from the base *g*.

55 *i* is the girth, whose ends *j* are flat, and from these flat ends extend the rectangular tenons *k*. The beveled sides *l* of the girth diverge from the ends *j*.

60 As shown in Fig. 5, the tenon *b* of the post when set upright serves to receive the tenon *e* of the cap and the tenon *k* of the girth, and this tenon *k* of the girth co-operates with both the tenon and the subtenon of the cap, and 65 the end bases *g* and *j* of the cap and girth also interlock.

65 By the construction described and by reason of the interlocking of the various tenons when the timbers are placed in position, as 70 shown in Fig. 5, none of the members can be driven back out of place by slipping of the beveled joint, and therefore in underground working it is possible for the miners to continue their blasting without any reference to 75 the working of the timber men building them.

What I claim is—

1. Round mine-timbers, having rectangular tenons projecting from flat bases at the ends of the said timbers, the sides of the timbers next 80 the bases being beveled.

2. Mine-timbers, comprising a post, cap and girth, each provided with truncated pyramidal ends having rectangular tenons projecting therefrom.

85 3. Mine-timbers, comprising a post, cap and girth, provided with beveled ends, flat bases, and interlocking rectangular tenons.

4. A mine-timber cap, having beveled ends, a flat base, a subtenon projecting from said 90

base, and a rectangular tenon projecting beyond the subtenon.

5. A mine-timber cap, having beveled ends, a flat base, a subtenon projecting from said base, and a rectangular tenon projecting beyond the subtenon, each of the parallel walls of two sides of the said tenon and subtenon being coincident.

6. A mine-timber cap, having beveled ends, 10 a flat base, a subtenon projecting from said base, and a rectangular tenon projecting be-

yond the subtenon, parallel walls of two sides of the said tenons being coincident, and the adjacent sides having their walls in different planes.

In testimony whereof I have hereunto set my hand this 2d day of February, A. D. 1904.

DAVID W. BRUNTON.
